UNITED STATES PATENT OFFICE.

ANDREW STROMDAHL, OF SOMERVILLE, MASSACHUSETTS, ASSIGNOR TO AUTOMATIC HAMMER COMPANY, OF BOSTON, MASSACHUSETTS, A CORPORATION OF NEW JERSEY.

AUTOMATIC HAMMER.

SPECIFICATION forming part of Letters Patent No. 732,466, dated June 30, 1903.

Application filed January 31, 1902. Serial No. 91,974. (No model.)

To all whom it may concern:

Be it known that I, ANDREW STROMDAHL, a citizen of the United States, and a resident of Somerville, in the county of Middlesex and State of Massachusetts, have invented new and useful Improvements in Automatic Hammers, of which the following is a specification.

My invention consists in sundry improvements in automatic hammers which are developed upon the type of hammer shown and described in Letters Patent of the United States, No. 694,898, issued to me on the 4th day of March, 1902. My improvements presently to be described contribute to the compactness, serviceability, and accuracy of the hammer.

In the drawings hereto annexed, Figure 1 is a side elevation of a hammer embodying my improvements. Figs. 2 and 3 show the two halves of the hammer-head. Fig. 4 is an elevation of the driver and actuator with the motion-transferring pinion in place. Fig. 5 is an elevation of the actuator with the cover-plate removed therefrom. Fig. 6 shows the cover-plate for the actuator. Fig. 7 is a vertical cross-section taken along the line 7-8 of Fig. 1, viewed from the right and showing the movable parts of the hammer closed within the head. Fig. 8 is a vertical cross-section on the same line as Fig. 7, but shows the movable parts extended. Fig. 9 is a detail showing the tack-feeder and its operating-cam in the position corresponding to the sectional view in Fig. 7. Fig. 10 is a detail of the tack-feeder and its operating-cam in position corresponding to the sectional view in Fig. 8. Fig. 11 is a detail showing the tack-raceway and gathering-blades. Fig. 12 is a detail showing the gathering-blade in end view; and Fig. 13 is a sectional view of the upper part of the tack-hopper, showing the lid raised.

I have shown my improvements as forming part of a lasting hammer or pincers, this being a tool to which such improvements are peculiarly adapted.

A is the upper, and A' the lower, handle of the pincers. a and a' are the jaws thereof. The jaws are slotted at a² and a³, as shown in dotted lines in Fig. 1, to admit the ham-

mer-head and tack-raceway. At a⁴ there is provided a convenient claw for the extraction of tacks.

B is the tack-hopper, a metal box provided with ears b², wherewith the hopper is attached to the jaw a by the bolts b³ and b⁴. The cover b is hinged with a spring-hinge b' and is normally closed thereby. The interior of the box B contains the deflector-plate b⁷ and has an inclined bottom b⁸. On the under side of the lid b there is secured the deflecting-hood b⁶, which overhangs the gathering-blades of the raceway in such manner as to deflect tacks onto the gathering-blades when the tool is wielded in the ordinary fashion.

C' are the lower and upper plates of the raceway, the plate C being slotted or double to accommodate tack-shanks and the plate or bar C' serving as a guard to overlie the tack-heads. This raceway is secured by having its upper head c fit within the aperture b⁵ in the hopper B, through which it protrudes, and by screws c³ and c⁴, which enter the side of the hammer-head. At the upper end of the raceway the gathering-blades C² are located. These are formed upon or of a piece of spring metal and are joined by the resilient clip c⁶, Fig. 12, which is so proportioned that it may be sprung over the end of the plate C and hug tightly thereto without the aid of other fastening.

It should be noted that the raceway-plates C C' lie against the side of the hammer-head D and that the point of entrance of tacks to the interior of the hammer-head is near the rear side of the head. This arrangement enables me to construct the hammer more compactly than is possible when the raceway leads to the front or nose of the hammer-head and lends proper space for giving the raceway the angle of inclination best adapted to the flow and feed of tacks. This disposition of parts also involves a mode of tack separation from the raceway which I believe to be novel and which lends materially to the effectiveness and accuracy of the tool's operation.

D is the hammer-head, which fits snugly in the jaw a and passes through a clearance-slot a² in the jaw a'.

E is the tack feeder or separator, F its op-

100

erating-cam, and G the catch wherewith the user of the tool regulates the excursions of the working parts within the hammer-head.

In Fig. 1 the visible parts of the tool are shown as assembled. The details of construction and the operation of parts are illustrated in the other figures.

Figs. 2 and 3 show the two parts of the hammer-head, which is a chambered shell vertically divided, the parts D' and D² forming the hammer-head D when united by rivets or screws, for which the holes d⁸ d⁹ d¹⁰ are provided. The chamber consists of a lower space d' and extensions d² and d³, the turret D³ extending above the body of the hammer-head to afford space for the spring d⁶. The hole d⁷ constitutes a bearing for the pinion-shaft to be described presently, and the hole e⁴ affords passage for the guide-rod of the feeder E. The section D² is laterally cut away at d⁵, where the raceway-plates adjoin the hammer-head. The chamber in the hammer-head is occupied by the driver and its actuator, which in general operate in the same manner as the similar parts shown in my Patent No. 694,898 aforesaid. These parts I have improved in construction and arrangement as follows: The actuator H comprises the rack-bar h, which is mounted on or integral with the foot H', which is a rectangular block, chambered at h' and vertically perforated at h³ for the admission of the driver I. The diagonal recess h² is provided for the reception of the stop-spring s, which normally closes the lower end h⁴ of the driver-passage h³. A notch h⁵ is also provided, which cooperates with the catch G. Only one notch h⁵ is here shown; but, if it be desired, others may be provided for the purpose of holding the actuator H in positions intermediate between full extension and complete closure. The recess h² is closed by the cover-plate K, which is screwed to the block H' at k' and provided with a T-shaped tack-opening at k. This tack-opening is so shaped and sized that any tack which can pass through it will be capable of being driven properly by the descent of the driver I and registers with the delivery end of the raceway on the outside and with the driver-passage h³ on the inside. The driver I is a rod which slides in the passage h³ and terminates in the rack-bar i. The pinion J stands between the racks h and i and meshes with both racks. It is centrally perforated with the flattened hole j, which receives the cam-shaft, presently to be described. The actuator, driver, and pinion are assembled, as shown in Fig. 4, and inserted in the hammer-head chamber, the actuator rack-bar h crowding the spring d⁶ into the turret-chamber d². The spring d⁶ thus normally thrusts the actuator H downward and by virtue of the rack-and-pinion connections the driver I upward.

The operation of the tack separating and driving mechanism is illustrated in Figs. 7, 8, 9, and 10. The feeder E is mounted on the slide-rod e⁸, which passes through the hole

e⁴, Figs. 2 and 3, in the hammer-head and is constantly urged toward the position shown in Fig. 8 by the spring e⁵. The feeder E has a follower-point e' at its upper end and a tack-separating finger e² at its lower end, which reciprocates across the lower end of the raceway C C'. The cam F, which controls the movements of the feeder E, is mounted on the cam-shaft f⁶, which is flattened in the middle so as to fit in the central hole of the pinion J, Fig. 4. This cam F is peculiarly constructed, so that the inward-feeding thrust of the feeder E is abrupt. The annularly-dished shell F', which constitutes the main body of the cam F, has an outer circumferential rim-cam surface f' and the snap-plate f². A partially-annular disk fits inside the rim-cam f' and turns upon the hub f⁴. A spring f⁵, anchored on the hub f⁴ and secured at its free end to the snap-plate f², normally holds the snap-plate against the pin f³, fixed in the shell F. The snap-plate is segmentally recessed to afford play over this pin f³. The rim-cam f' slopes down to the point f⁶; but the snap-plate is flat, having its upper surface only a little below the high part of the cam f'. As under the driving influence of the pinion J the cam F is turned to the right, as viewed in Figs. 1 and 7, the follower-point e' rides out on the snap-plate f² until its terminus f⁷ passes under the follower e', when the spring e⁵ pulls the feeder in and causes its feeding-finger e² to pass across the lower end of the raceway C C'. This happens when the actuator H is extended, as in Fig. 8, and the tack-opening k of the cover-plate K is in register with the lower end of the raceway, so that the lowermost tack is thrust from the line in the raceway sidewise through the opening k into the driver-passage h³, the driver I being at the top of its stroke at this instant. The acting face of the feed-finger e² is flat and fits into the tack-opening k, so that the tack thus fed is absolutely confined in the driver-passage, the nose of the driver being above it, the spring s below, and the tack-opening k closed by the feed-finger e². It often happens that a badly-sized or misshapen tack gets into the raceway and is of such a character that it refuses to be fed from the raceway into the driver-passage. The raceway is so proportioned that a tack which will enter it must necessarily progress with the rest to the delivery end of the raceway, so that no trouble need be apprehended until the critical point of separation from the raceway is reached; also, if a tack is capable of passing through the tack-hole k into the driver-passage it cannot fail to be driven out and into the work. The only troublesome place is the point of separation, and here the construction of my improved hammer places the tack in a freely-accessible position. If a tack refuses to be passed into the driver-passage, the operator is made aware of the fact by the failure of the tool to drive a tack, as expected. He then presses the spring end of the feeder-

rod e^3 until the feeder is clear of the cam F and raceway-blades C C' and turns the feeder E slightly to one side. Then inserting an awl, needle, or other suitable instrument in the notch c', Fig. 11, in the blade C, he picks out the refractory tack, replaces the feeder E, and goes on with his work. Thus the correction of faults due to occasional bad tacks is the work only of an instant, and there is no necessity of fussing with the tool or losing time by going to the factory machinist, as is too often the case with hammers wherein the tack-passages are inaccessible. The driving stroke of the hammer causes the actuator H to close with the hammer-head, thus impelling the driver I to force the tack past the spring s into the work by means of the pinion connection J, and as the pinion connection J turns to perform this office it carries the cam F with it, turning it to the left, as viewed in Fig. 9. Now the sloping rim-cam f' lifts the follower e', and the follower e' pushes the snap-plate f² against the spring f⁵ until the follower e' has ridden high enough on the rim-cam f' to clear the snap-plate, which springs back into position, as shown in Fig. 9. This cycle of movements is repeated with each down and up stroke of the hammer unless the operator permits the catch G to engage the notch h⁵ with its toe g², which is constantly urged into catch position by the spring g³, attached to the handle A at g⁴, the catch G turning on its pivot g. The finger-hold g' enables the operator to control the catch G with a finger of the hand that wields the hammer. The sudden movement of the feeder E is believed to have its advantages, but a simple disk cam may be used instead of the snap-cam F. Such a simple cam is shown in my Patent No. 694,898 aforesaid and need not be described here.

The sectional construction of the hammer-head D enables its chambered recesses to be formed with facility and accuracy. The mode of forming the driver-passage in the actuator-block lends compactness, strength, and simplicity to the structure. The device of lateral separation of tacks from the raceway does away with the necessity for double-pointed feed fingers or separators and enables me to use the plain-faced finger, which serves also as a guard or back-stop to prevent accidental return of a tack once fed into the driver-passage, and the snap action of the feed-finger causes the feed devices to delay action until the way is wholly clear for a tack to move into position under the driver.

The general mode of handling and using this improved tool is like the mode described in my Patent No. 694,898 aforesaid and need not be repeated here.

What I claim, and desire to secure by Letters Patent, is—

1. In a tool of the character described, the combination of a tack-hopper, a chambered hammer-head, a tack-driver and a hollow driver-actuator sliding in the hammer-head,

the driver-passage located in the actuator, the actuator provided with a lateral tack-opening and a tack-raceway leading from the hopper overlapping the side of the hammer-head and provided with a tack-delivery end at the side of the hammer-head, and a tack-feeder, to push tacks from the delivery end of the raceway into the hammer-head. 75

2. In a tool of the character described, the combination of a tack-hopper, a chambered hammer-head, a tack-driver and a hollow driver-actuator sliding in the hammer-head, the driver-passage located in the actuator, the actuator provided with a lateral tack-opening, a tack-raceway leading from the hopper and secured externally to the side of the hammer-head, a recess in the side of the hammer-head for the reception of the raceway, a tack-receiving opening in the side of the hammer-head, and a tack-feeder to push tacks from the delivery end of the raceway into the hammer-head. 85

3. In a tool of the character described, the combination of a tack-hopper, a chambered hammer-head, a tack-driver and a hollow driver-actuator sliding in the hammer-head, the driver-passage located in the actuator, the actuator provided with a lateral tack-opening and a tack-raceway leading from the hopper and delivering to the hammer-head, the delivery end of the raceway being accessible from the outside, and a tack-feeder to push tacks from the delivery end of the raceway into the hammer-head. 95

4. In a tool of the character described, the combination of a tack-hopper, chambered hammer-head, a tack-driver and a hollow driver-actuator sliding in the hammer-head, the driver-passage located in the actuator, the actuator provided with a lateral tack-opening, tack-raceway having its delivery end at the side of the hammer-head, a tack-receiving aperture in the side of the hammer-head, a tack-feeder, mounted to reciprocate across the raceway, and feeder-actuating devices whereby the feeder is reciprocated to push tacks successively from the raceway into the interior of the hammer-head. 110

5. In a tool of the character described, the combination of a tack-hopper, chambered hammer-head, tack-driving devices therein comprising a tack-driver and a hollow driver-actuator containing a driver-passage, a tack-raceway, leading from the hopper and having its delivery end at the side of the hammer-head, an opening in the side of the driver-actuator into the driver-passage adapted to admit a tack of normal character and to exclude a misshapen tack, the delivery end of the raceway being accessible from the outside for purposes of removing refractory tacks. 125

6. In a tool of the character described, the combination of a tack-hopper, tack-raceway, and chambered hammer-head, a tack-driver and hollow driver-actuator sliding in the hammer-head, the driver-passage located in the actuator, the actuator provided with a lateral

tack-opening, a tack-feeder movably mounted upon the hammer-head, feeder-actuating devices, the feeder provided with means whereby at will it may be displaced from its 5 normal position, to afford access to the tack beneath it.

7. A tool of the character described, the combination of tack-supplying devices comprising a raceway; a chambered hammer-head, tack - driving mechanism within the head, a tack-feeder, an operating-cam therefor, comprising a feeder-sustaining surface, an abrupt descent therefrom, and a feeder-lifting cam, whereby the feeder is replaced 10 upon the sustaining-surface, a spring for the feeder, and connections between the tack-driving devices and feeder-operating cam.

8. In a tool of the character described, the combination of a spring-controlled tack-feeder 15 provided with a cam-follower, and a feeder-operating cam; the said cam having a feeder-supporting surface, movable with relation to the cam-body and provided with an abrupt

termination, and a cam-surface whereby the feeder-follower is replaced upon the supporting-surface, the said supporting-surface yielding to the movement of the cam-follower during the act of said replacement, substantially as described. 25

9. In a tool of the character described, the combination of a spring-controlled tack-feeder provided with a cam-follower, a feeder-operating cam comprising a rim-cam, a feeder-supporting surface consisting of a snap - disk mounted within the rim-cam, a spring to control the snap - disk, whereby the said disk yields to permit the rise of the cam-follower upon the rim-cam, and moves to position under the follower when the latter clears it, substantially as described. 30 35 40

Signed by me at Boston, Suffolk county, Massachusetts, this 25th day of January, 1902.

ANDREW STROMDAHL.
